OSCILLATION GENERATION

Jacob van Slooten, Eindhoven, Netherlands, assignor, by mesne assignments, to Radio Corporation of America, New York, N. Y., a corporation of Delaware

Application June 25, 1938, Serial No. 215,742
In Germany September 2, 1937

2 Claims. (Cl. 250—36)

This invention relates to a retroactively coupled thermionic generator comprising a grid condenser and a leak resistance.

It is a well-known fact that in oscillators of this kind a phenomenon occurs which is referred to hereinafter as "over-oscillation" or "blocking" and which consists in that the oscillations set up by the oscillator are periodically interrupted. In practice, this phenomenon often occurs with oscillators serving for the production of short waves. Thus, for example, in the construction of superheterodyne receiving sets arranged for the reception of wavelengths from 15 to 50 meters this phenomenon is particularly troublesome in the local oscillator.

In order to decrease as far as possible the tendency of an oscillator comprising a grid condenser and a leak resistance to over-oscillate, it has previously been proposed to use a small grid condenser. It is also well known that the use of a small leak resistance renders the oscillator more stable.

The use of a small grid condenser and also that of a small leak resistance entails disadvantages that render it desirable to use other measures for stabilizing an oscillator.

The disadvantage of a small grid condenser consists in the latter being of the order of magnitude of the grid-cathode capacity which in series with the grid condenser is included in the grid circuit in parallel with the high-frequency impedance across which the feed-back voltage is applied to the grid. This has the effect of only part of the retroactively coupling voltage supplied to this impedance occurring across the grid and the amplitude of the oscillations set up by the oscillator being consequently small.

In the use of a small leak resistance, this resistance brings about a high attenuation of the frequency-determining oscillatory circuit. The latter disadvantage is particularly prevalent with an oscillator serving as the local oscillator in a superheterodyne receiver which is arranged both for the reception of waves from about 15 to 50 meters and for the reception of at least one band of longer waves. Since the impedance of the frequency-determining oscillatory circuit of an oscillator increases on the reception of short waves being switched over to a band of longer waves, the attenuating effect of the leak resistance on the oscillatory circuit increases. This necessitates switching over of the leak resistance on the reception of the band of longer waves to a higher value, which renders the set complicated.

The invention has for its object to provide

measures reducing the tendency toward over-oscillation (blocking) to a minimum value so that the said disadvantages do not occur.

According to the invention, this object is achieved by the arrangement of means which in the case of an increase of the amplitude of the oscillations produced bring about an additional charge of a condenser included in the grid circuit.

In one form of construction, these means comprise a diode which is connected in parallel to the grid-cathode space of the oscillator valve and whose anode is connected to the grid. In another form of construction of the oscillator according to the invention, that part of the cathode conductor which is common to the grid and anode circuits includes a condenser which is shunted by a choke coil. In a further form of construction, that part of the cathode conductor which is common to the grid and anode circuits includes a condenser which is shunted by a resistance and whose electrode connected to the cathode is connected to the grid of the oscillator valve via the grid leak resistance.

In order that the invention may be clearly understood and readily carried into effect, it will now be described more fully with reference to the accompanying drawing, in which:

Fig. 1 shows one form of construction of an oscillator according to the invention whose operation will be more clearly understood by reference to the curves shown in Fig. 2.

Figs. 3, 4 and 5 show other forms of construction of an oscillator according to the invention.

Fig. 1 shows an oscillator which contains a discharge tube 1 comprising a cathode, a grid and an anode. The frequency-determining circuit which is constituted by the parallel combination of a condenser 2 and an inductance coil 3 is included in the grid circuit and the anode circuit includes a feed-back coil 4. In addition, 5 and 6 designate a grid condenser and a leak resistance respectively which are included in the circuit in well known manner and are proportioned in the usual manner.

The circuit hitherto described has a tendency to over-oscillate, that is, block. In order to explain the cause of this phenomenon, let us assume a given position of equilibrium at which the oscillator sets up oscillations of constant amplitude. In this position of equilibrium, the grid condenser 5 is charged by the grid current to a voltage which is higher negative than the voltage at which the anode current is suppressed in the absence of oscillations. The condenser voltage determines the grid bias of the oscillator valve and thus the point

50
55

of the anode-current grid-voltage characteristic curve to which the oscillator is adjusted.

Referring to Fig. 2, the anode-current grid-voltage characteristic curve of the tube 1 is represented by *a*. The working point of the characteristic curve is designated by *b* and the oscillations set up in the circuit 2-3 by the oscillator are represented by the curve *c*.

When for some reason or other, for example on account of a small increase of the anode direct voltage, the amplitude of the oscillations generated exceeds the said constant value, the effective mutual conductance of the oscillator valve increases, since the anode direct current increases to a higher extent than the amplitude of the oscillations generated. Due to the increasing mutual conductance of the oscillator valve, the amplitude of the oscillations produced increases to a still higher extent, which in turn results in an increase of the mutual conductance. Thus the above-assumed position of equilibrium becomes unstable and this lack of stability is the cause of the phenomenon of over-oscillation.

According to the invention, in order to suppress the tendency to over-oscillate, the grid-cathode space of the oscillator valve has connected in parallel with it a diode 7 whose anode is connected to the grid of the tube 1.

If the amplitude of the oscillations produced increases, the condenser 5, due to the presence of the diode 7, is charged by the grid current which increases with an increasing amplitude of the oscillations set up as well as by the current that passes through the diode 7. Consequently, in the case of an increasing amplitude of the oscillations produced, the condenser 5 will have occurring across it an additional negative voltage which displaces the working point of the characteristic curve to a point at which the mutual conductance is lower. In the circuit shown in Fig. 1, the effective mutual conductance would therefore increase, in the case of a deviation from the position of equilibrium, by reason of an increase in the amplitude of the oscillations to be set up. On the other hand, the additional voltage (i. e., the negative bias) across the condenser 5 would bring about a decrease of the effective mutual conductance. Thus, both actions counteract each other, which avoids any disturbance in the position of equilibrium of the amplitude of the oscillations set up.

In the form of construction shown in Fig. 3 the diode 7 is arranged within the oscillator valve, since the latter comprises an additional electrode 8 arranged adjacent the control grid and the cathode of the oscillator valve. This supplementary electrode 8 constitutes with the cathode a diode which increases the current that passes through the grid circuit in the case of an increasing amplitude of the oscillations set up, said current bringing about an additional charge of the condenser 5.

In the form of construction shown in Fig. 4, that part of the cathode conductor which is common to the grid and the anode circuits includes a condenser 9 shunted by a choke coil 10. The anode direct current passes through the choke coil which constitutes a short-circuit for the condenser. In the case of an increase of the amplitude of the oscillations set up, a variation in

the mean anode current occurs. Thus the condenser 9 becomes charged so that a negative voltage occurs across the condenser 9, said voltage being supplied to the grid of the valve 1 and displacing the working point of the oscillator valve to a point of less steepness.

A circuit in which a resistance 11 is substituted for the choke coil required in Fig. 4 is shown in Fig. 5. In this circuit, the grid leak 6 is connected to that point of the condenser 9 which is connected to the cathode so that the direct voltage drop which occurs across the resistance 11 due to the mean anode current is prevented from being supplied to the grid. The voltage which occurs across the condenser 9 in the case of a variation of the mean anode current is, however, supplied via a condenser 5 to the grid of the oscillator valve 1.

What is claimed is:

1. A retroactively coupled oscillator comprising an electron discharge device containing a grid, an anode and a cathode, a frequency determining circuit having one terminal connected to said grid through a grid condenser, a choke coil shunted by a by-pass condenser having one end connected to said cathode and the other end connected to the other terminal of said frequency determining circuit, a leak resistor connected between said grid and said last end of said choke coil, a connection from said anode also to said last end of said choke coil, said connection being coupled to said frequency determining circuit for feeding back energy from said anode, said device considered together with said grid condenser and leak resistor functioning to bias said grid in proportion to the strength of oscillations, said by-pass condenser being a path of low impedance to energy of the operating frequency and the combination of said choke coil and by-pass condenser having high impedance to sudden changes in average current passing therethrough, whereby said combination of choke and by-pass condenser function to impart an additional voltage to said grid which is proportional to the rate of change of the average anode current.

2. A retroactively coupled oscillator comprising an electron discharge device containing a grid, an anode and a cathode, a frequency determining circuit having one terminal connected to said grid through a grid condenser, a choke coil shunted by a by-pass condenser having one end connected to said cathode and the other end connected to the other terminal of said frequency determining circuit, a leak resistor connected between said grid and said last end of said choke coil, means for feeding back energy from said anode to said frequency determining circuit, said device considered together with said grid condenser and leak resistor functioning to bias said grid in proportion to the strength of oscillations, said by-pass condenser being a path of low impedance to energy of the operating frequency and the combination of said choke coil and by-pass condenser having high impedance to sudden changes in average current passing therethrough, whereby said combination of choke and by-pass condenser apply an additional bias to said grid in proportion to the algebraic value of the rate of change of the oscillation amplitude.
